DESIGN.

R. WATERHOUSE.

ORNAMENTATION OF A NECKSCARF.

No. 15,920.

Patented Mar. 3, 1885.

Attest,

Geo. D. Smallwood,

Inventor:

Rufus Waterhouse.

UNITED STATES PATENT OFFICE.

RUFUS WATERHOUSE, OF NEW YORK, N. Y.

DESIGN FOR THE ORNAMENTATION OF A NECKSCARF.

SPECIFICATION forming part of Design No. 15,920, dated March 3, 1885.

Application filed December 24, 1884. Term of patent 3½ years.

To all whom it may concern:

Be it known that I, RUFUS WATERHOUSE, a citizen of the United States, residing in the city, county, and State of New York, have invented and produced a new and original Design for the Ornamentation for a Neckscarf, of which the following is a full, clear, and exact description, reference being had to the accompanying drawing, in which it is represented.

The body of my scarf is represented of hexagonal form, having a center-piece, *a*, of triangular shape, provided with check ornamentation, and flaps *b b*, divided from the center-piece by folds of *Y* form. The flaps are shown as gathered together by a band or collar, *d*, provided with check ornamentation, and holding them in a narrow contracted neck, *e*. *c* is the neck-strap.

It will be seen that in this design the center-piece *a*, and the band or collar *d* are of different appearance from the flaps *b b*, so as to produce a variegated effect.

I claim—

1. The design for the ornamentation of a

neckscarf, as shown and described, the same consisting of a body of hexagonal form, having a center-piece, *a*, provided with a check pattern, as shown, flaps *b b*, divided from the center-piece by folds of *Y* form, and band or collar *d*, surrounding the flaps.

2. The design for the ornamentation of a neckscarf, as shown and described, the same consisting of a body of hexagonal form, triangular center-piece *a*, flaps *b b*, divided from the center-piece by folds of *Y* form, and a band or collar, *d*, provided with a check pattern, as shown, and surrounding the flaps.

3. The design for the ornamentation of a neckscarf, as shown and described, the same consisting of a body of hexagonal form, triangular center-piece *a*, having a check pattern, as shown, flaps *b b*, divided from the center-piece by folds of *Y* form, and a band or collar, *d*, having a check pattern, as shown, and surrounding the flaps.

RUFUS WATERHOUSE.
